MAGAZINE RACK

Milton Weinman, Chicago, Ill.

Application November 24, 1958, Serial No. 53,480

Term of patent 14 years

(Cl. D33—2)

Fig. 1 is a perspective view of a magazine rack embodying my new design;

Fig. 2 is a side elevational view of the same;

Fig. 3 is a top plan view thereof;

Fig. 4 is a bottom plan view thereof; and

Fig. 5 is an end elevational view thereof.

The side and end of the magazine rack not shown is substantially the same as the side and end shown respectively.

I claim:

The ornamental design for a magazine rack, as shown and described.
